UNITED STATES PATENT OFFICE

110,901

DESIGN FOR A CUP OR ANALOGOUS ARTICLE

Herman C. Kupper, New York, N. Y.

Application December 15, 1936, Serial No. 66,544

Term of patent 7 years

To all whom it may concern:

Be it known that I, Herman C. Kupper, a citizen of the United States, residing in the Borough of Manhattan, city, county, and State of New York, have invented a new, original, and ornamental Design for a Cup or Analogous Article, of which the following is a specification, reference being had to the accompanying drawings, forming a part thereof.

Fig. 1 is a top plan view of the article showing my design;

Fig. 2 is a side elevational view partly in medial section;

Fig. 3 is a perspective view thereof.

I claim:

The ornamental design for a cup or analogous article, substantially as shown and described.

HERMAN C. KUPPER.
